CONSTANT TENSION LET-OFF MECHANISM

Carl D. Brown, Hopedale, Mass., assignor to
Draper Corporation, Hopedale, Mass., a corporation of Maine

Application March 5, 1937, Serial No. 129,169

10 Claims. (Cl. 139—110)

The present invention pertains to let-off mechanisms for looms, and has more particular reference to the construction and arrangement of the whip roll structure of such mechanisms and the correlation of the same with other parts of the let-off mechanism.

Mechanisms of the type mentioned commonly include a rotatable warp beam carrying the warp supply, suitable means for controlling the rate of rotation of the warp beam, and a whip roll structure including a yielding whip roll for supporting and tensioning the warp sheet. In one commonly used form of such structure, the whip roll is depressed vertically by an increased tension of the warp sheet, and positive let-off means is controlled from the whip roll for increasing the speed of rotation of the warp beam when the whip roll is so depressed. This prior construction is subject to the disadvantages that the raising and lowering of the whip roll raises and lowers the warp sheet, and that the mechanism must include means for feeding of the warp supply on the warp beam and varying the operation of the let-off means in accordance with the diameter of such supply.

Various other let-off mechanisms and whip roll structures have been proposed heretofore, only a few of which have been used commercially. These other mechanisms have been objectionable in various respects which need not be herein enumerated in detail.

I propose to provide a let-off mechanism having a rotatable warp beam and let-off means for controlling the rate of rotation of the warp beam as aforesaid, and a novel whip roll structure which shall be so constructed that it will maintain a uniform tension on the warp sheet and which shall be simple and inexpensive to construct and efficient in operation.

To the end mentioned, the invention in one of its aspects comprises a let-off mechanism having a warp beam, let-off means for controlling the rate of rotation of the warp beam, and a whip roll structure comprising parallel racks positioned above the warp beam, a whip roll supported by gears which roll along the racks and yielding means for so urging the whip roll longitudinally of the racks against the warp sheet as to maintain a uniform tension thereon.

The foregoing and other objects of the invention are accomplished in the construction illustrated on the accompanying drawings, of which:

Fig. 1 is a perspective view of a loom having the preferred embodiment of my invention applied thereto, but with certain parts removed;

Fig. 2 is an end view of certain parts of the mechanism of Fig. 1 with the whip roll housing in place;

Fig. 3 is a plan view of a part of such mechanism, with the housing removed;

Fig. 4 is a diagrammatic view illustrating the operation of the mechanism; and

Fig. 5 is a view in cross-section taken approximately on line 5—5 of Fig. 3.

The drawings show only my improved let-off mechanism and part of a loom to which the same has been applied, parts of the loom not shown being of usual construction forming no part of the present invention. The conventional parts that are shown include the loom sides 1, 2 which are connected by cross members such as the girt 3, and a bearing 4 which is one of a pair of bearings fixed to the loom sides and which rotatably support a warp beam 5. The warp beam 5 includes a conventional barrel 6 and heads 7, 8, and contains the warp supply from which the warp sheet is taken. The warp sheet extends upwardly from the warp beam at W¹ and forwardly, substantially horizontally at W² to the front of the loom. The portion W² of the warp sheet passes through a harness 9 and other usual devices not shown.

The drawings show the preferred form of my supporting means comprising a pair of fixed racks positioned above the warp beam, one at each side of the loom. The rack 10 consists of a series of rack teeth formed on the upper surface of a bracket 11 which is bolted to the left hand loom side 1 at 12. The right hand rack 13 may be similarly formed and supported, the racks being parallel and preferably extending horizontally forwardly and rearwardly of the loom.

There is also shown the preferred whip roll structure, which includes a whip roll 14 and a gear at each end thereof, only the left hand gear 15 being shown. These gears are fixed to the ends of a shaft 16 and the whip roll 14 is rotatably mounted on the shaft. The gears mesh with and roll along racks 10, 13, the entire whip roll structure being thus movable rectilinearly forwardly and rearwardly of the loom. The warp sheet extends upwardly and forwardly about the whip roll 14 and the whip roll structure is yieldingly urged rearwardly by means to be described, to cause the whip roll to bear rearwardly against the warp sheet and tension the same. It will be apparent that since the racks 10, 13 are substantially parallel to the forwardly extending portion W² of the warp sheet the whip roll struc-

ture may be rolled forwardly or rearwardly along the racks without raising or lowering the warp sheet.

The aforementioned means for urging the whip roll structure rearwardly preferably includes a sheave 17, a flexible element 18 and yielding means such as a tension spring 19. The sheave 17 is fixed to the gear 15 as by being set-screwed to the shaft 16 between the gear and the left hand end of the whip roll 14. The flexible element 18 may consist of a chain which extends about the sheave 17 and is fixed thereto by a screw 20. The lower end of the spring 17 may be fixed to the floor or other support on which the loom rests, and the upper end of the spring is connected to one end of the element 18. These parts are so constructed and arranged that the spring pulls on the flexible element 18 in a direction to roll the whip roll structure rearwardly along the racks. A similar sheave, flexible element and spring may be provided at the right hand side of the loom and such parts are shown at the left of Fig. 1. However, the two racks 10, 13 and the gears connected by the shaft 16, will keep the whip roll in proper alignment so that two sheaves and springs are not necessary.

The preferred whip roll structure and spring controlling means therefor are so constructed and arranged that the whip roll structure is gradually moved forwardly along the supporting racks as the quantity, or diameter of the warp supply on the warp beam decreases. Fig. 4 shows in full lines the position of the warp sheet and of the whip roll 14 when the warp beam is full, and in broken lines the positions of the warp sheet and whip roll when the warp supply is substantially exhausted. It will be apparent that as the warp supply becomes depleted the decreasing angle between the portions W¹ and W² of the warp sheet results in an increased forward pull on the whip roll even though the tension of the warp sheet remains constant. The sheave 17 is, however, a compensating sheave, that is, the sheave is so shaped that as the whip roll structure rolls forwardly the flexible element 18 acts on an increasing radius of the sheave to thereby provide a constantly increasing resistance to the forward movement of the structure.

The compensating sheave 17 may be variously shaped to produce various predetermined relations between the forward movement of the whip roll structure and the quantity of warp supply remaining on the warp beam. The particular sheave 17 shown is so shaped that, the tension on the warp sheet and other factors remaining constant, the forward movement of the whip roll structure is directly proportional to the quantity of warp supply that has been woven off the warp beam.

The supporting means for the whip roll, comprising rack 10 and gear 15, are enclosed by a housing 21, Fig. 2. This housing may consist of a single casting having top end and side walls, the housing being bolted to the bracket 11 at 22, 23. The housing 21 is shown in full lines on Fig. 2 but is removed in other views and its position indicated by broken lines. A similar housing is provided at the other side of the loom to enclose the other rack and gear, but is not shown on the drawings.

The end wall of the housing 21 is provided with a slot 24 and a reduced extension 25 on the shaft 16 projects out through this slot. The housing and whip roll structure are provided with relatively movable indicia for visibly indicating the

position of the whip roll structure on the supporting racks. In the preferred embodiment, such indicia comprise a visible mark or series of marks 26 on the housing 21 and a member 27 consisting of a collar loosely mounted on the extension 25 and having a pointer 28 which moves with the whip roll structure adjacent the marks 26. A rod 29 fixed in this pointer slides in a bearing 30 on the housing 21 and prevents the collar and pointer from turning on the shaft 16 extension 25. Where, as above described, the whip roll structure is arranged to gradually move forwardly in predetermined relation to the quantity of warp supply on the warp beam, the marks 26 and the pointer 28 indicate at a glance the approximate quantity of warp remaining on the warp beam. Furthermore, the tension on the warp sheet may be determined merely by comparing the quantity of warp on the warp beam with the quantity indicated by the marks and pointer. This method of determining warp tension is at least as accurate as the prior practice of pushing on the warp sheet with the hand, and prevents soiling or other damage to the warp which was caused by such prior practice.

In accordance with some aspects of my invention, the character of the let-off means for controlling the rate of rotation of the warp beam is not material. The drawings show one good form of positive let-off means, wherein a shaft 31 is geared to the beam head 7 by a pinion, not shown, and the shaft 31 is positively rotated by a worm 32 which drives a worm gear 33 on such shaft. The worm 32 is fixed on a shaft 34 which revolves in bearings in a bracket 35 fixed to the loom side 1. A ratchet wheel 36 is fixed to the shaft 34. A pawl carrier 37, having pawls 38, oscillates on the shaft 34. A rod 39, pivoted to the pawl carrier is pulled forwardly by a reciprocating link 40 to thereby rotate the ratchet wheel and shaft 34 in the direction to effect let-off of the warp sheet from the warp beam. The return stroke of the rod 39 and pawl carrier 37 is effected by a compression spring 41.

The positive let-off means shown, as thus far described, is similar to the corresponding parts of the Bartlett let-off which is well-known in the art. I have, however, provided a novel means for controlling the let-off means, to vary the speed of rotation of the warp beam in accordance with the position of the whip roll structure on its supporting means. The preferred form of such means comprises a link 42 and lever 43. The link has a head provided with a slot 44 in which the end of the extension 25 of the shaft 16 slides. The other end of this link is pivoted at 45 to the upper end of the lever 43. The lever 43 is pivoted intermediate its ends on a stud 46 carried by the loom side 1. The lower end of the lever has an apertured head 47 which embraces the rod 39. A spring 48 pulls the lower end of the lever 43 forwardly to a position determined by engagement of the forward end of the slot 44 with the extension 25. A collar 49 is fixed to the rod 39 and engages the head 47 to limit rearward movement of the rod by spring 41. The spring 48 is appreciably stronger than the spring 41.

It will be apparent that when the whip roll structure is at its rearwardmost position on the supporting racks 10, 13, the head 47 will be at its forwardmost position. This results in the rod 39 being held from moving very far rearwardly and, since the link 40 always moves forwardly to a predetermined position, the stroke of the rod

39 and pawl carrier 37 will be relatively short. Then as the whip roll structure moves forwardly, the head 41 will be moved rearwardly and the length of stroke of the pawl carrier correspondingly increased, to thereby increase the speed of rotation of the warp beam.

The mechanism just described will serve to vary the speed of rotation of the warp beam whenever, in the operation of the loom, the whip 10 roll structure is moved ahead or back of the position which it should occupy relative to the diameter of the warp supply remaining on the warp beam. Thus, the construction is such that the let-off mechanism need not be adjusted to take 15 up or let off the warp sheet when the cloth take-up (not shown) is manipulated after a pick out, because the whip roll structure will move to maintain tension on the warp sheet and the speed of rotation of the warp beam will be automatically 20 varied thereby. This variation in the speed of rotation of the warp beam as a result of a temporary change in the position of the whip roll structure will, of course, result in the whip roll structure promptly returning to its proper pre- 25 determined position.

A further important feature of the preferred embodiment of the invention is that, in this construction the speed of rotation of the warp beam is automatically increased as the warp supply 30 becomes depleted. The parts shown are so designed that as the whip roll structure moves forwardly on its supporting racks the speed of rotation of the warp beam is increased at the proper rate (within the limitations of a pawl-and- 35 ratchet drive) to compensate for the decrease in diameter of the warp supply. In this way I have eliminated any necessity for manual adjustment of the let-off and have eliminated the above mentioned means for feeding of the warp supply, 40 which were required in prior let-off mechanisms.

Having fully disclosed the preferred embodiment of my invention, I claim:

1. In a let-off mechanism for looms, the combination of a rotatable warp beam, supporting 45 means comprising a pair of spaced parallel racks positioned above said warp beam and extending generally forwardly and rearwardly of the loom, a whip roll structure including gears meshing with and rolling along said racks, and a whip roll 50 supported by said gears for movement therewith along with said racks, the warp sheet from said warp beam extending upwardly and forwardly about said whip roll, means yieldingly urging said whip roll rearwardly along said racks to 55 tension the warp sheet, and let-off means for controlling the rate of rotation of said warp beam.

2. In a let-off mechanism for looms, the combination of a rotatable warp beam, supporting 60 means comprising a rack at each side of the loom above said warp beam, said racks being parallel, a whip roll structure including a whip roll and a gear at each end of said whip roll, said gears meshing with and rolling along said racks, the 65 warp sheet from said warp beam extending upwardly and forwardly about said whip roll, a sheave fixed to one of said gears, a flexible element extending about and fixed to said sheave, yielding means connected to said element and 70 pulling the same in a direction to urge said whip roll against the warp sheet, and let-off means for controlling the rate of rotation of said warp beam.

3. In a let-off mechanism for looms, the combination of a rotatable warp beam, supporting 75

means comprising parallel racks positioned one at each side of the loom above said warp beam, a whip roll structure adapted to move longitudinally of said racks, said structure comprising a whip roll and a gear at each end of said whip roll, said gears meshing with and rolling along said racks, the warp sheet from said warp beam extending upwardly and forwardly about said whip roll, a compensating sheave fixed to one of said gears, a flexible element extending about and fixed to said sheave, yielding means connected to said element and pulling the same in a direction to urge said whip roll against the warp sheet and let-off means for controlling the rate of rotation of said warp beam. 15

4. In a let-off mechanism for looms, the combination of a rotatable warp beam, supporting means comprising a rack at each side of the loom above said warp beam, said racks being parallel and extending generally forwardly and rearwardly of the loom, a whip roll structure including gears meshing with and rolling along said racks and a whip roll supported by said gears, the warp sheet extending from said warp beam upwardly and forwardly about said whip 20 roll and thence forwardly to the front of the loom, a compensating sheave fixed to one of said gears, a flexible element extending about and fixed to said sheave, yielding means pulling on said element in a direction to urge said whip roll 25 rearwardly along said racks to thereby tension the warp sheet, and means for controlling the rate of rotation of said warp beam. 30

5. In a let-off mechanism for looms, the combination of a rotatable warp beam, supporting 35 means comprising a rack at each side of the loom above said warp beam, said racks being parallel, a whip roll structure including a whip roll and a gear at each end of said whip roll, said gears meshing with and rolling along said racks, means 40 controlling said whip roll structure so that the latter is gradually rolled forwardly along said racks in predetermined relation to the quantity of warp supply on said warp beam, a housing enclosing each of said gears and racks, and indicia comprising a mark on one of said housings and a member carried by said structure and moving adjacent said mark to indicate the position of said structure on said racks. 45

6. In a let-off mechanism for looms, the combination of a rotatable warp beam, supporting 50 means comprising a rack at each side of the loom above said warp beam, said racks being parallel, a whip roll structure including a shaft having a fixed gear at each end thereof and a whip roll on 55 said shaft, said gears meshing with and rolling along said racks, the warp sheet from said warp beam extending upwardly and forwardly about said whip roll, a compensating sheave fixed on said shaft, a flexible element extending about 60 and fixed to said sheave, yielding means pulling on said element in a direction to urge said whip roll against said warp sheet, and let-off means for controlling the rate of rotation of said warp beam. 65

7. In a let-off mechanism for looms, the combination of a rotatable warp beam, supporting 70 means comprising a rack at each side of the loom above said warp beam, said racks being parallel and extending generally forwardly and rearwardly of the loom, a whip roll structure including a shaft having a fixed gear at each end thereof and a whip roll rotatably mounted on said shaft, said gears meshing with and rolling along 75 said racks, the warp sheet from said warp beam

extending upwardly and forwardly about said whip roll and thence forwardly to the front of the loom, a compensating sheave fixed on said shaft, a flexible element extending about and fixed to said sheave, yielding means pulling on said element in a direction to urge said whip roll rearwardly against the warp sheet, said yielding means and said sheave being constructed and arranged to provide a constantly increasing 10 resistance to forward movement of the whip roll as the warp supply on said warp beam becomes depleted, and means for controlling the rate of rotation of said warp beam.

8. In a let-off mechanism for looms, the combination of a rotatable warp beam, supports comprising fixed racks positioned one at each side of the loom above said warp beam, said racks being parallel and extending generally forwardly and rearwardly of the loom, a whip roll structure 20 including a shaft having a fixed gear at each end thereof and a whip roll rotatably mounted on said shaft, said gears meshing with and rolling on said racks, the warp sheet from said warp beam extending upwardly and forwardly about 25 said whip roll and thence forwardly substantially parallel to said racks, means yieldingly urging said whip roll structure rearwardly to thereby tension the warp sheet, said means and said structure being so constructed and arranged that 30 said structure is gradually moved forwardly along said racks as the warp supply on said warp beam becomes depleted, and let-off means controlled by said whip roll structure for varying the speed of the rotation of said warp beam in accordance 35 with the position of said structure on said racks.

9. In a let-off mechanism for looms, the combination of a rotatable warp beam, supports comprising fixed racks positioned one at each side

of the loom above said warp beam, said racks being parallel and extending generally forwardly and rearwardly of the loom, a warp tensioning whip roll structure supported by said racks and constructed and arranged to be gradually moved 5 forwardly on said racks by the warp sheet as the warp supply on said warp beam becomes depleted, said structure including a shaft having a fixed gear at each end thereof and a whip roll rotatably mounted on said shaft, said gears meshing with 10 and rolling on said racks, means yieldingly opposing said forward movement of said structure, and let-off means controlled by said structure for varying the speed of rotation of said warp beam 15 in accordance with the position of said structure on said racks.

10. In a let-off mechanism for looms, the combination of a rotatable warp beam, supports comprising fixed racks positioned one at each side of the loom above said warp beam, said racks being 20 parallel and extending generally forwardly and rearwardly of the loom, a warp tensioning whip roll structure supported by said racks and constructed and arranged to be gradually moved forwardly on said racks by the warp sheet in pre- 25 determined relation to the diameter of the warp supply on said warp beam, said structure including a shaft having a fixed gear at each end thereof and a whip roll on said shaft, said gears meshing with and rolling on said racks, means acting 30 on said structure to maintain a constant tension on the warp sheet as said structure is moved forwardly as aforesaid, and let-off means controlled by said structure for increasing the speed of rotation of said warp beam as the structure moves 35 forwardly on said racks.

CARL D. BROWN.
